Patent expires April 30, 1958

2 Claims. (Cl. 179—171.5)

1

The present invention relates to a device for radiophonic modulation of a high frequency oscillation or for the amplification of a modulated high frequency oscillation, and has the object of improving the efficiency of radiotelephony transmitters.

It is known that in the modulating tubes or in the tubes amplifying the modulated high frequency, the voltage corresponding to the amplitude of the non-modulated high frequency only attains one half of the maximum voltage corresponding to the saturation limit of the tubes, the latter being attained only on modulation peaks. Owing to this spare power which it is necessary to provide for in order to permit the correct transmission of the modulation peaks, it follows that during most of the time, the tube operates only under half load conditions, corresponding to a comparatively low efficiency, of the order of 30%, while on modulation peaks, for a modulation of 100%, the efficiency is substantially twice as great.

The modulating or amplifying device according to the present invention has the object to remedy this drawback and is characterised by the fact that it comprises two tubes, one of which is saturated by the non-modulated amplitude of the carrier, while the second tube provides the additional power necessary for the modulation peaks.

It will be understood that under these conditions the first tube, which is saturated by the non-modulated amplitude of the carrier, will operate constantly with its maximum efficiency, while the second tube, operating intermittently at the moments corresponding to the modulation peaks, will also work under full voltage during its operating periods, so that the efficiency of the entire arrangement will be a maximum.

By way of example there has been described below and represented on the annexed drawing embodiments of the invention.

Figure 1 is a wiring diagram in which the device according to the invention is used as a modulated HF amplifier.

Figures 2 to 6 are the current curves illustrating the operation of the device, and

Figures 7 and 8 are diagrams of two alternative embodiments in which the device according to the invention is used as a modulator.

The device of Fig. 1 shows diagrammatically a radiotelephony transmitter comprising a generator 1 of a high frequency carrier wave, a source 2 providing the low frequency voltage, and a modulator 3 in which the high and low frequencies are combined for supplying the modulated carrier into the output winding 4. The amplifier accord-

2

ing to the invention includes two tubes 5 and 6, preferably connected in push-pull, with their grids connected to the terminals of the winding 4. The amplifying tube 5 receives through the conductor 7 a normal biasing voltage, and the plate voltage applied to the tube is determined in such a manner that the tube will be saturated when its grid is supplied with the non-modulated carrier. In order that the modulation peaks be amplified by the second tube 6, its grid is given by the conductor 8 to a high negative bias by the source 20 determined in a manner that this tube will only start working after the modulated high frequency voltage has attained the value corresponding to the saturation of the first tube 5, so that the tube 6 will operate only during modulation peaks. The amplified currents supplied by both tubes add up in the common output circuit 9, in which the complete modulation curve is thus found again. This manner of operation is illustrated in Figs. 2 to 6. Fig. 2 showing the voltage of the non-modulated carrier wave, the amplitude of which brings about the saturation of tube 5, while Fig. 3 shows the modulated high frequency current supplied by this tube 5. As a result of the saturation of this tube, it will be seen that only the hollows 10 in the modulation are reproduced, while the modulation peaks 11, shown in dotted lines, are eliminated. Figure 4 shows the modulated high frequency current supplied by the second tube 6, which will only pass, for the reasons indicated above, during modulation peaks, while Fig. 5 shows the resulting current in the common output circuit 9 of both tubes. Owing to the different values of the bias of both tubes, the latter will generally not reproduce identically the parts of the modulation curves corresponding to the modulation hollows and peaks respectively, so that the curve of the modulated current will present, as shown in Fig. 5, angular parts such as 12, 12', 12'', etc. Means are thus provided to bring the operating point of the second tube, 6, automatically back, during the operating periods of this tube, to a region in the neighbourhood of that of tube 5, so as to ensure a perfect junction of the curves representing the currents of either tube, as shown in Fig. 6. This result may be obtained by means of an auxiliary bias applied to the tube 6 during modulation peaks, for instance, as represented in Fig. 1, by applying to the grid of this tube, through the means of a potentiometer 13, a voltage proportional to the low frequency modulation voltage tapped off on the modulation device 2. An adjustment of the potentiometer 13 will offset the oper-

ating point of tube 6 for obtaining the required reproduction curve for the modulation peaks. This auxiliary bias may, of course, also be obtained in any other suitable manner.

The junction of the curve of the current supplied by the tube amplifying the peaks with the curve of the current supplied by the tube which is saturated by the carrier may also be obtained without resorting to the use of a variable bias of the former tube, of the type described below. It will merely be necessary to provide fixed, but different voltages to either grid and either plate of the tubes and to adjust these voltages in such a manner that the peak tube will commence supplying current at the precise moment when the other tube begins to be saturated. Such an adjustment merely requires that a certain relation be observed between the fixed voltages of the electrodes.

If:

n is the ratio of the load resistance to the internal resistance of the tubes,

k the amplification factor of the tubes,

E_2 the constant part of the control voltage of the peak tubes, and

U_1 the constant negative bias of the first tube, this relation is:

$$\frac{E_2}{U_1} = \frac{I+k}{I + \frac{n}{2}(I+k)}$$

The application of different voltages to each of the four considered electrodes also permits an adjustment of the entire device in such a manner as to obtain other interesting properties. Thus, if the constant part E_1 of the control voltage of the saturated tube is made zero, the current will be caused to flow starting from the value zero of the exciting modulated alternating voltage, thereby permitting to provide for a modulation of 100%. It may be proved that if this condition, as well as the preceding condition, are satisfied, the reproduction of the modulated wave by the device is absolutely linear and free from distortion; the efficiency on the carrier may attain 70% for a suitable choice of the ratio n of the load resistance to the internal resistance of the tubes.

In the arrangement of Fig. 7, the two tubes 5 and 6 of the device according to the invention are used as modulators, the carrier wave produced by the generator 1 and the low frequency from the source 2 being both applied to the control grids 14 and 15 of these tubes. In the alternative arrangement of Fig. 8 the two modulating tubes 5 and 6 are pentodes, the control grids

14 and 15 of which receive the high frequency while the low frequency is applied to the suppressor grids 16, 17. In these two arrangements, the auxiliary biasing device of tube 6 has not been shown, which may be realised in any of the manners indicated above.

What I claim is:

1. Apparatus for modulating a high frequency carrier oscillation and for amplifying the modulated high frequency carrier oscillation comprising, a high frequency carrier source, a modulation voltage source, two thermionic tubes, means for applying the carrier frequency and the modulating voltage to said tubes, means for biasing one of said tubes for operation only at oscillation amplitudes not exceeding the unmodulated carrier level, means for biasing the other of said tubes for operation only at oscillation amplitudes exceeding the unmodulated carrier level, and
- 10 means for applying an auxiliary variable biasing voltage to the second tube for varying the operating point thereof whereby the response characteristic of the two tubes are rendered coextensive.
- 15 2. Apparatus for modulating a high frequency carrier oscillation and for amplifying the modulated high frequency carrier oscillation comprising, a high frequency carrier source, a modulation voltage source, two thermionic tubes, means for applying the carrier frequency and the modulating voltage to said tubes, means for biasing one of said tubes for operation only at oscillation amplitudes not exceeding the unmodulated carrier level, means for biasing the other of said tubes for operation only at oscillation amplitudes exceeding the unmodulated carrier level, means for applying an auxiliary variable biasing voltage depending on the frequency of the modulating voltage to the second tube for varying the operating point thereof whereby the response characteristic of the tubes are rendered coextensive.
